JOHN EUGENE FEIERTAG, OF MILFORD, OHIO.

DESIGN FOR A SPOON-HOLDER.

59,632.

Specification for Design.

Patented Nov. 15, 1921.

Application filed March 14, 1921. Serial No. 452,328. Term of patent 3½ years.

To all whom it may concern:

Be it known that I, J. EUGENE FEIERTAG, a citizen of the United States of America, residing at Milford, in the county of Clermont and State of Ohio, have invented a certain new, original, and ornamental Design for Spoon-Holders, of which the following is a specification, reference being had to the accompanying drawings, forming a part hereof.

the outer face of my design for spoon holder.

Fig. 2 is a perspective view illustrating the reverse face.

I claim—

The ornamental design for a spoon holder as shown.

J. EUGENE FEIERTAG.
